Mirror Frame.

No. 12.217.

Patented April 5, 1881.

Fig 2.

UNITED STATES PATENT OFFICE.

JOHN JOSEPH CHARLES SMITH, OF COLLEGE POINT, NEW YORK, ASSIGNOR
TO COLLEGE POINT RUBBER COMPANY, (LIMITED,) OF SAME PLACE.

DESIGN FOR A MIRROR-FRAME.

SPECIFICATION forming part of Design No. 12,217, dated April 5, 1881.

Application filed July 16, 1880. Term of patent 7 years.

To all whom it may concern:

Be it known that I, JOHN JOSEPH CHARLES SMITH, a citizen of the United States, residing at College Point, in the county of Queens and State of New York, have invented Improvements in Designs for Mirror-Frames, of which the following is a specification.

My invention relates to a design for mirror-frames to be molded in rubber, celluloid, or other plastic material, with a handle encircled by grooved ribs, after the manner of bamboo, and connected with the head or back by a grated neck consisting of a number of divergent bars, so as to impart to the whole mirror the form and appearance of a fan.

In the accompanying drawings, Figure 1 is a front view of the mirror. Fig. 2 is a back view.

The mirror-back A is decorated, as repre-

sented in Fig. 2, with pictorial representations of birds, plants, &c. The handle H is formed with circumferential ribs R, grooved, as shown, after the similitude of bamboo, and is connected with the fan-shaped head by a grated neck, N.

Having thus described my invention, the following is what I claim as new therein, and desire to secure by Letters Patent:

The design for a hand-mirror, consisting of a back or frame, A, of substantially the form shown, a handle, H, encircled with grooved ribs R, and a neck of divergent bars connecting said frame and handle, all substantially as set forth.

JOHN JOSEPH CHARLES SMITH.
